(57) **CLAIM**

The ornamental design for a planar connector assembly, as shown and described.

DESCRIPTION

FIG. 1 is a perspective view of the planar connector assembly of the invention, in fully closed condition;

FIG. 2 is an end elevational view of the planar connector assembly, the opposite end elevational view being a mirror image thereof;

FIG. 3 is a top plan view of the planar connector assembly; FIG. 4 is a bottom view of the planar connector assembly; FIG. 5 is a right side elevational view of the planar connector assembly;

FIG. 6 is a left side elevational view of the planar connector assembly;

FIG. 7 is an elevational view showing the outside face of one of the plates comprising the planar connector assembly;

FIG. 8 is an end elevational view of the plate, the opposite end elevational view being a mirror image thereof;

FIG. 9 is an elevational view of the inside face of the plate;

FIG. 10 is a top plan view of the plate;

FIG. 11 is a bottom view of the plate;

FIG. 12 is an elevational view showing the outside face of the other plate comprising the planar connector assembly;

FIG. 13 is an end elevational view of the other plate, the opposite end elevational view being a mirror image thereof; FIG. 14 is an elevational view of the inside face of said other plate;

FIG. 15 is a top plan view of said other plate; and,

FIG. 16 is a bottom view thereof.

The elements of the claimed design have been shown in a detached manner in FIGS. 7-16 for clarity of illustration.

The elements of the claimed design are shown separately for clarity of illustration.
